Altis

UNITED STATES PATENT OFFICE.

HAROLD FOWLER, OF PORT HOPE, ONTARIO, CANADA.

PARLOR GAME.

1,300,368.

Specification of Letters Patent. Patented Apr. 15, 1919.

Application filed May 15, 1918. Serial No. 234,767.

To all whom it may concern:

Be it known that I, HAROLD FOWLER, of the town of Port Hope, in the county of Durham, in the Province of Ontario, Canada, 5 have invented certain new and useful Improvements in Parlor Games, of which the following is the specification.

My invention relates to improvements in parlor games, and the object of the invention is to devise a game in connection with 10 aviation, and which I term "The Great Air Raid Game".

My invention consists of a board divided into preferably one hundred squares, ten on 15 a side, each square being designated by peculiar characteristics, such as a bombing canal, bombing ammunition dump, bombing zeppelin hangars, etc., and the game board being otherwise arranged and the game played 20 by moves of men indicating an aeroplane, such moves being determined by the use of dice.

Figure 1, is a plan view of a board.

Fig. 2, is a detail of one of the men making the moves.

In the drawings like characters of reference indicate corresponding parts in each figure.

1 is my game board and 2 is one of the 30 men, which consists of a block 2' having a plate 2² inserted in a notch therein and a representation of an aeroplane 2³ thereon. The board 1 is divided into a series of squares preferably ten on each side or one 35 hundred squares in all. These squares are also numbered starting at the lower left hand corner at 1 to 100 on a backward and forward principle as indicated from the bottom upward.

40 There are two main paths on the surface of the board, the lost in the mist path A starting from square 63 (not numbered) and ending with square 1, and the home path B starting with square 81 and ending with 45 square 1 (not numbered). The majority indicate clouds and several of them different objects against which aeroplanes are generally sent.

I term my game "The Great Air Raid

Game" and it can be played by any number 50 of players, each player having one man or aeroplane. These aeroplanes are differently colored and are designed to be moved according to the throw of dice. 55

ers, each player having one man or aeroplane. These aeroplanes are differently colored and are designed to be moved according to the throw of dice.

The object of the game is to get as many 60 points as possible.

The rules are as follows:

The first player to reach or pass square 54 gets 10 points or the player which first lands on a square representing a hangar battery or wireless station counts 10 points. 65 The other players landing on 54 or passing there do not count any.

The first one to reach square 100 counts 40 points, the others after that counting 20.

All players have to land on No. 100 by 70 exact throw of the dice.

When a player lands on No. 7 on which it says "Engine misfiring return home", the player must return to No. 1 by exact throws of the dice before he can start again. 75

When a player lands on No. 31 he is supposed to have been hit by an anti-aircraft gun shell and is either out of the game or may start again from No. 1.

When a player lands on No. 63 he is supposed to have got lost in the clouds and must follow the path or A trail by throwing the dice until he gets home. But in the count up he may count whatever points he has obtained before getting lost. If, however, he 85 lands in the same square with another player who is not lost he may start again from whatever number he is on.

When a player reaches 100 he still has to go home down the B trail to No. 1 and he 90 has to get to No. 1 by exact throw.

If he lands on the No. 6 of the B trail he is supposed to have run out of gasoline and must stay there and is out of the game.

If however a player lands on No. 5 of the 95 B trail the one on No. 6 may start again. The fellow on No. 5 is supposed to have given him enough gas to get home with.

The winner is the one who has the most points among those who succeeded in getting back to No. 1.

What I claim as my invention is—

- 5 An aviation parlor game comprising a board divided into squares, having peculiar characteristics common to aviation, the board having two main paths on its surface, the lost in the mist path and the home path and
- 10 movable parts designed to represent aero-

planes, these being moved from one square to another according to the rules of the game as set forth, the moves being governed by throw of dice.

HAROLD FOWLER.
